LOOP-BUCKLE

Robert J. Hodge, West Haven, Conn., assignor to
The American Buckle Company, West Haven,
Conn., a corporation

Application July 13, 1935, Serial No. 31,244

3 Claims. (Cl. 24—73)

This invention relates to an improvement in loop-buckles, and particularly to loop-buckles for use on shoulder-straps of overalls, for engagement with the button on the overall-apron.

The object of this invention is to produce in a simple manner a buckle having a depending swinging loop to engage with the buckle, and which, when engaged, will firmly hold the button so that accidental disengagement cannot take place, and the invention consists in the construction as hereinafter described and particularly recited in the claims.

In the accompanying drawing:

Fig. 1 is a front view of a loop-buckle constructed in accordance with my invention and shown as engaged with a button;

Fig. 2 is a sectional view on the line 2—2 of Fig. 1;

Fig. 3 is a sectional view showing the loop turned to permit the loop to be engaged with or removed from a button;

Fig. 4 is a sectional view on the line 4—4 of Fig. 1, enlarged;

Fig. 5 is an under-side view;

Fig. 6 is a rear view;

Fig. 7 is a rear view with the loop detached;

Fig. 8 is a perspective view of the loop detached;

Fig. 9 is a front view showing a modified form of my invention;

Fig. 10 is a vertical sectional view of the same;

Fig. 11 is a front view of another modified form of my invention; and

Fig. 12 is a vertical sectional view of the same.

The buckle consists of a frame comprising a top-bar 15, a continuous bottom-bar 16, side-bars 17 and 18, and one or more transverse-bars 19 and 20. Preferably, and as shown in Figs. 1, 2 and 3 of the drawing, the frame is struck up from sheet-metal and the edge 21 of the frame is turned inwardly, as are also the lower edge 22 of the top-bar 15, the upper edge 23 of the bar 19, the lower edge 24 of the bar 19, the upper edge 25 of the bar 20, the lower edge 26 of the bar 20, and the upper edge 27 of the lower-bar 16. The lower edge of the lower-bar 16 is formed with lugs 28 which are adapted to be rolled to form bearings 29 for the ends 30 of a wire loop 31, and adjacent to each bearing is a notch 32 to clear the sides of the loop.

The loop depends below the lower-bar to an extent somewhat less than the diameter of the button 33 on the overall-apron 34 with which it is to be connected. The suspender-strap 35 is webbed with the frame in the usual manner. To

engage the button with the loop, the loop is turned rearwardly as shown in Fig. 3 of the drawing, so that the button may readily pass through it. Then, when the loop is turned downwardly, it causes the head of the button 5 33 to pass forwardly and extend above the lower-bar 16 of the frame, so that the button cannot be withdrawn from the loop until the loop has been turned rearwardly as described. Instead of forming the frame from sheet-metal, it may be 10 formed from wire, as shown in Figs. 9 and 11 of the drawing.

In Fig. 9, the lower-bar 36 of the frame has a downward offset 37 at the center, and the ends 38 of the loop 39 are folded around the lower 15 frame on opposite sides of the offset 37, so that the distance between the offset 37 and the lower end of the loop is less than the diameter of the buckle with which it is to be used.

In Fig. 11 of the drawing, I have shown the 20 lower-bar 40 formed with upturned bends 41 on opposite sides of the center, around which offset portions the ends 42 of a loop 43 are turned, so as to pivotally connect the loop with the frame, and in this construction, the distance between the central portion of the lower-bar and 25 the outer end of the loop 43 is less than the diameter of the button to which it is to be connected.

In the forms shown in Figs. 9 and 11, the loop 30 must be turned rearwardly to permit the engagement of the loop with the button or to permit the removal of the same.

I thus provide in a very simple manner a loop-buckle comprising a frame and a button-loop 35 pivotally connected with the lower-bar thereof.

It will be understood by those skilled in the art that my invention may assume varied physical forms without departing from my inventive concept, and I, therefore, do not limit my invention to the specific embodiments herein chosen for illustration, but only as indicated in the appended claims.

I claim:

1. A loop-buckle comprising a frame having 45 a continuous lower bar, and a wire loop pivotally connected with the lower-bar of the same, the distance between the lower edge of said bar and the lower end of the loop being less than the diameter of a button with which it is to be engaged, whereby the upper edge of the button, when entered into the loop, will project over the said lower bar.

2. A loop-buckle comprising a sheet-metal frame having a lower-bar, the edges of which 55

lower-bar are turned inwardly, the said lower-bar formed with lugs adapted to be rolled to form bearings at the rear of the said bar and combined with a wire loop having its ends engaged by said lugs, whereby said loop is pivotally connected with the frame.

3. A loop-buckle comprising a sheet-metal frame having a lower-bar, the edges of which

lower-bar are turned inwardly, the said lower-bar formed with lugs and with notches adjacent to the inner edges of said lugs, said lugs adapted to be rolled to form bearings at the rear of the said bar and combined with a wire loop having its ends engaged by said lugs, whereby said loop is pivotally connected with the frame. 5

ROBERT J. HODGE.
